US0D1102120S

(12) United States Design Patent (10) Patent No.: US D1,102,120 S
(45) Date of Patent:  *Nov. 18, 2025

(54) SHOE

(71) Applicant: NIKE, Inc., Beaverton, OR (US)

(72) Inventor: Leon Gu, West Linn, OR (US)

(73) Assignee: NIKE, Inc., Beaverton, OR (US)

(*) Notice: This patent is subject to a terminal disclaimer.

() Term: 15 Years

(21) Appl. No.: 29/947,166

(22) Filed: Jun. 13, 2024

(51) LOC (15) Cl. 02-04

(52) U.S. Cl.
